CLAIM

The ornamental design for a storage container, as shown and described.

DESCRIPTION

FIG. 1 is an isometric view of a storage container showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 an exploded view thereof; and,

FIG. 9 an isometric bottom exploded view showing my design. The portions of the storage container shown in broken lines form no part of the claimed design.
